FIG. 2. is a front view of the screw of FIG. 1;

FIG. 3 is left side view of the screw of FIG. 1; and

FIG. 4 is right side view of the screw of FIG. 1.

FIG. 5 is a perspective view of a screw according to one embodiment;

FIG. 6. is a front view of the screw of FIG. 5;

FIG. 7 is left side view of the screw of FIG. 5; and

FIG. 8 is right side view of the screw of FIG. 5.

FIG. 9 is a perspective view of a screw according to one embodiment;

FIG. 10. is a front view of the screw of FIG. 9;

FIG. 11 is left side view of the screw of FIG. 9; and

FIG. 12 is right side view of the screw of FIG. 9.

FIG. 13 is a perspective view of a screw according to one embodiment;

FIG. 14. is a front view of the screw of FIG. 13;

FIG. 15 is left side view of the screw of FIG. 13; and

FIG. 16 is right side view of the screw of FIG. 13.

FIG. 17 is a perspective view of a screw according to one embodiment;

FIG. 18. is a front view of the screw of FIG. 17;

FIG. 19 is left side view of the screw of FIG. 17; and

FIG. 20 is right side view of the screw of FIG. 17.

FIG. 21 is a perspective view of a screw according to one embodiment;

FIG. 22. is a front view of the screw of FIG. 21;

FIG. 23 is left side view of the screw of FIG. 21; and

FIG. 24 is right side view of the screw of FIG. 21.

FIG. 25 is a perspective view of a screw according to one embodiment;

FIG. 26. is a front view of the screw of FIG. 25;

FIG. 27 is left side view of the screw of FIG. 25; and

FIG. 28 is right side view of the screw of FIG. 25.

FIG. 29 is a perspective view of a screw according to one embodiment;

FIG. 30. is a front view of the screw of FIG. 29;

FIG. 31 is left side view of the screw of FIG. 29; and

FIG. 32 is right side view of the screw of FIG. 29.

FIG. 33 is a perspective view of a screw according to one embodiment;

FIG. 34. is a front view of the screw of FIG. 33;

FIG. 35 is left side view of the screw of FIG. 33; and

FIG. 36 is right side view of the screw of FIG. 33.

FIG. 37 is a perspective view of a screw according to one embodiment;

FIG. 38. is a front view of the screw of FIG. 37;

FIG. 39 is left side view of the screw of FIG. 37; and

FIG. 40 is right side view of the screw of FIG. 37.

FIG. 41 is a perspective view of a screw according to one embodiment;

FIG. 42. is a front view of the screw of FIG. 41;

FIG. 43 is left side view of the screw of FIG. 41; and

FIG. 44 is right side view of the screw of FIG. 41.

FIG. 45 is a perspective view of a screw according to one embodiment;

FIG. 46. is a front view of the screw of FIG. 45;

FIG. 47 is left side view of the screw of FIG. 45; and,

FIG. 48 is right side view of the screw of FIG. 45.

The broken lines in the drawings illustrate portions of the screw, and form no part of the claimed design.
